stein, trustees

Application July 13, 1942, Serial No. 450,704

14 Claims. (Cl. 198—179)

1

In Bergstein Patent No. 2,206,761 issued July 2, 1940, there are disclosed machines and methods for package closure particularly in relation to closing the extending liner mouth and end flaps of lined containers. In our Patent No. 2,277,289 we have disclosed improved means and methods relating to this same general field. Our present invention relates to machines and methods for affecting package closures on containers similar to those involved in the aforesaid patents; and our present invention is particularly adapted to the carrying out of the process disclosed in Bergstein Patent No. 2,166,389 issued July 18, 1939.

The object of our invention is to provide a novel and improved method and means for retaining lined or unlined cartons in erect form while sealing or closure operations are being performed thereon. One of the advantages of our novel retaining means is the positioning of the package retaining fingers in open position to permit ready insertion of the package without the need for accurate register. Our invention further provides for automatic closure of said fingers, occasioned by the insertion of the package itself, accurate control of the package body during the various sealing operations, and automatic ejection of the container at its desired station upon completion of the sealing operations.

These general objects and others which will be apparent as the description proceeds, we accomplish by those mechanisms, methods and structures, and by the arrangements and combinations of parts, all as hereinafter described in certain exemplary embodiments, and particularly defined in the claims at the end of these specifications.

In the drawings:

Figure 1 is a side elevation of a packaging machine similar to that described in our Patent No. 2,277,289, but with parts broken away and other parts in section and showing certain improvements to be herein described.

Figure 2 is a horizontal sectional view taken along line 2—2 of Figure 1.

Figure 3 is an enlarged sectional view taken along the line 3—3 of Figure 1.

Figure 4 is a front elevation of a carton carrying device having further improved features and advantages and showing also a simplified and improved means for spreading or elongating the carton liners, said spreading device being integrally associated with the carton carrier.

Figure 5 is an enlarged sectional view taken on line 5—5 of Figure 4, showing the position of the carton retainer parts in closed position.

Figure 6 is a view similar to Figure 5, but showing the parts in an intermediate or neutral position preparatory to insertion of a carton.

Figure 7 is a view similar to Figures 5 and 6, but showing the parts in an extremely open posi-

2

tion as will occur during ejection of a carton from the machine.

Figure 8 is a side elevation showing a packaging machine employing the improved carton carriers and liner spreading devices of Figure 4. The figure is fragmentary in character with parts broken away and other parts in section and with various support members for the folding and sealing elements omitted so as to more clearly to illustrate certain features of our invention.

Figure 9 is a horizontal sectional view taken along the line 9—9 of Figure 8.

Figure 10 is a fragmentary enlarged sectional view taken along the line 10—10 of Figure 8, the lower end of an initially squared up carton being shown so as to illustrate how a carton is received in the cage for initial closure.

Figures 11 and 12 are detail plan views of certain cam plates which control ejection of the cartons from the cages of Figure 4.

Figure 13 is a vertical section taken along the line 13—13 of Figure 9, illustrating operation of improved ejecting and segregating mechanism when ejecting a finally filled and sealed carton from the machine.

Figure 14 is a section similar to Figure 13, but illustrating an alternate position of the parts as will occur during ejection of an initially set up or empty carton.

Referring to the machine of Figures 1 and 2, we have illustrated an embodiment similar to that described in our Patent No. 2,277,289 before mentioned, the present embodiment incorporating improved features to be hereinafter set forth.

As in the aforementioned patent, the machine has a frame member 1 providing journaled bearings for the shafts of a pair of sprockets 2 and 3, over which the conveyor chain 4 operates in a horizontal flight. The driving power is supplied through sprocket 2, which is driven by a motor 5 operating through suitable drive means generally indicated at 6. The chain 4 carries a series of interspaced carriage members 7 which are guided in proper alignment about the conveyor path by suitable channeled guide members generally indicated at 8.

Referring to Figure 3, the members 7 are each furnished with a stud 9 which provides a rotatable mounting for a gear 10 and a square plate 11 which is fixed to the gear, both being rotatably mounted on the stud, with respect to the carriage. The pivoted members 10 and 11 form a turret mounting for the carton carrying devices.

In the embodiment of Figure 3 the plate 11 has fixedly mounted thereon a casting 12 and a mandrel or hollow block 13. However, and as seen in Figure 1, the mandrels 13 may be supplanted or replaced where desired by carrying devices or cages generally indicated at 14 and to be later described in detail.

During passage of the conveyor members about the path of the machine, as indicated by the arrows in Figure 2, the inner sides or edges of the turret plates 11 have sliding engagement against guide rails or bars arranged to prevent rotation of the turrets. Starting at the point or station A of Figure 2, the carrying devices will be conveyed to the left, being locked against rotation during travel by the rail 15. After passing about the sprocket 3 the plates 11 are again engaged by a guide rail 16 which terminates at the position of a short rack 17 mounted on the machine frame, and arranged to mesh with the gears 10 as they pass by it. Thus these racks produce a rotation of the turret assemblies through, say, 90°, changing the orientation of the cartons with respect to their direction of travel. After passing the rack 17, the turrets are again locked against rotation by the rail 18. Thereafter, and in their further course of travel, the racks 19, 20 and 21 each function to turn the turrets through additional quarter revolutions in the manner just described, while the rails 22, 23 and 24 serve to prevent undesired rotation during intervening travel. When they have reached station K, where the cartons will be ejected, the turrets will thus have been turned through a complete revolution, and the cages or mandrels will have returned to their original relationship to the direction of travel as at station A, and will again be in proper position to receive another carton.

In the machine of Figures 1 and 2, alternate carriages bear mandrels and the rest bear cages. The mandrels 13 serve to carry the cartons during initial setting up of the container, i. e. sealing and folding of the closure members on one end, e. g. the bottom. The cages 14 serve to carry the cartons which have already been closed on one end, and which will have been filled, through operations for the final closure of the package, e. g. the sealing and folding of the top members after insertion of the contents. It will thus be apparent that the machine shown may serve the dual purpose of initially setting up the containers preparatory to filling and of finally sealing and closing them after they have been filled. It will also be seen later that either of these operations may be performed singly or that both may be carried out simultaneously in the machine, the sealing and folding mechanism provided being adapted to seal and fold either end of the package, and an ejection mechanism, to be later described, being provided to segregate the filled from the unfilled containers at the point of ejection.

Referring to Figures 4 and 5, we have shown further improvements in carton carrying devices and also in means for spreading and elongating the liners, said means for spreading and elongating the liners being integrally associated with the carton carrier. As here shown, the carton carrier comprises a cage-like device generally indicated at 100, the spreading means 101 being supported thereabove by a suitable bracket 102.

It is to be pointed out that the spreading device provides automatic and assured registering of the fingers to the carton, because, since the spreaders are carried in fixed relation to the carton holding means, the fingers will always be in proper aligned position in relation to the liner, in contradistinction to the machine of Figure 1, where the spreaders, moving separately, have to be timed as to their travel in relation to the travel of the carton. By making the spreaders an integral part of the carton holding means,

the need for spacing or timing on the machine is eliminated. With this arrangement, any number of carton holding devices can be used, spaced any distance apart, because they are self-timing in their spreading functions as they travel about the machine while the remainder of the instrumentalities may be fixed elements. This permits much higher production and greatly simplifies the mechanism.

10 It is further to be pointed out that this same general arrangement of integral spreaders and carton holding means could be used to fold in the two inner carton flaps instead of spreading the liner mouth and/or folding the flaps outward and apart.

15 Referring to Figures 4 and 5, an improved carton holder or cage is here shown, and comprises a pair of standards 110 and 111 which serve to support an upper assembly including a pair of arms generally indicated at 112, which will grasp the carton near its upper end, and a lower assembly of like parts indicated at 113 for grasping the carton near its lower end. Both of the assemblies may be identical excepting that 20 the lower one carries a platform or bottom gauge member 114 which supports the carton in proper relation to the sealing and folding devices. Cages or holders as distinguished from mandrels may be employed both in effecting bottom closures of 25 unfilled cartons and in effecting top closures of 30 filled cartons.

Figure 5 shows the closed position of the lower pair of cage members or arms 116 and 117, a carton retained therein being indicated by the 35 broken lines 115. The arms are of a bell crank formation, each having a short forwardly extending portion 118 with an inwardly bent outer end or finger 119 to engage the carton as shown. The arm 117 is pivotally mounted on the standard 40 111 as at 120 and has an angularly related longer arm 121, extending rearwardly, and with a slot formation 122 slidably engaging a stud 123, the stud being fixed at its lower end in the rearwardly extending arm 124 of member 116, which member 45 is pivoted at 125 to the standard 110. By the stud and slot arrangement described, it will be apparent that movement of the arms about their pivoted mountings 120 and 125 will occur in opposite relation, and that the arms may occupy positions as shown in Figures 5, 6 and 7.

50 For controlling the positions of the arms, the stud 123 is engaged by a link 126 which at its other end carries a cam roller 127 and is pivotally attached, as at 127a, to a lever 128 and to 55 a bracket 128a on a rod 129.

The lever 128 is pivotally attached as at 128a to a bracket 130 fixed on the standard 110 and has a downwardly extending stud 131. The bracket 130 has an adjustable abutment or screw 132 60 for limiting the movement of the lever. Near its outer end, the rod 129 is slidably mounted in a stud 133, pivoted to a bracket 134 carried on the standard 111. Mounted upon the rod 129, a compression spring 135 urges the parts to the position of Figure 5, the spring bearing at one end against the bracket 128a and at its other end against the body 136 of a latch element through which the rod 129 slidably passes. The body of the latch element may be fixed to the stud 133 65 so as to form an integral part thereof, or as shown may be a separate piece held in proper operative relation by the action of the spring 135 holding it against the stud 133.

70 For retaining the parts in the neutral position (Figure 6) the rod 129 has a notch 137 which will

be engaged by a tooth 138 of the latch, as shown. The tooth 138, formed in an element 139 which is pivotally mounted in the latch body 136 as at 140, is urged to engage the notch by a suitable spring 141. The relation of the notch 137 and tooth 138 is such that positive locking of the members in the position of Figure 6 will not occur, but the latch will become disengaged permitting the spring 135 to return the parts to the position of Figure 5 when sufficient inward pressure is applied against the arms 121 and 124, as will occur when the operator places a carton, indicated at 115, into the cage. Thus a trigger action is established in the change of positions between Figures 6 and 5 and when, during the course of its travel in open position, the operator inserts a carton, the fingers of the cage automatically snap closed on it, holding it securely in position. The trigger action, being controlled by the introduction of the package itself, automatically closes the cage at the precise moment required, and mechanical means for closing are rendered unnecessary.

With the carton retained in the cage as in Figure 5 it will be carried through the machine during the sealing and closing operations. At the point of ejection, the members of the cage will be moved to the position of Figure 7 by the action of stationary cams to be later described. Movement of the members to this position will cause the carton to be pushed outward from the machine by the arms 121 and 124 which will assume the position shown to remove the carton from the arms 116 and 117. If the change of position occurs rapidly, the carton will acquire momentum sufficient to transfer it to an adjacent platform or conveyor for disposal as required.

From an examination of Figure 7, it will become apparent that the spring 135 will tend to hold the parts in the position shown, due to the fact that the thrust of the spring is past center with reference to a line intersecting the pivoted mountings of lever 128 and rod 129. For returning the parts to the position of Figure 6, so that another carton may be loaded into the device, the downwardly extending stud 131 carried on lever 128 will be engaged by a suitable cam track to be later disclosed.

While the foregoing description has related to the lower assembly of arms and fingers generally indicated at 113 in Figure 4, it will be understood that the upper assembly generally indicated at 112 in that figure may be identical in construction and operation. However, it will be apparent that the assemblies may be individually controlled. This feature is employed to our advantage in the operations of ejecting the cartons from the machine, for which ejection we have provided cam elements to be later described, which engage the rollers 127 and are arranged to operate the upper assembly 112 slightly ahead of the lower assembly 113 or vice versa depending on whether the particular cage involved carries a finally filled and closed container or a container which is empty and on which only the initial closing of the ultimate bottom has been performed, the mode of ejection being part of a segregating operation and mechanism to be presently described.

With the arrangement herein disclosed, the cage of Figure 4 is adapted for carrying cartons during initial closure, the pair of rollers 127 being located so as to be engaged and operated by upper and lower cam plates respectively shown at 142

5 6 and 143 in Figure 14. However, and for the cages which are to carry the finally filled and closed containers, the rollers 127 on alternate occurrences of the cages may be placed or arranged in planes not coinciding with the cam plates 142 and 143. This is illustrated in Figure 13 where the rollers 127 have been replaced by upper and lower rollers 144 arranged in planes coincident with cam plates 145 and 146. By this arrangement alternate occurrences of the cages and the ejection of the containers therefrom will be individually controlled, that is, the cam plates 142 and 143 will control ejection of the initially closed or empty containers, and the cam plates 145 and 146 will control ejection of the finally closed containers, the cages having the cam rollers located as at 127 serving to carry the cartons during initial closure and the cages having the cam rollers located as at 144 serving to carry the cartons during final closure. The cages for filled or unfilled cartons may be alternately arranged, and if desired, may be visually distinguished, as by color.

Figures 13 and 14 also show an improved segregating device which is synchronized with the ejection mechanism to determine disposal of the cartons. The device comprises a chute 150 having a wide opening or mouth 151 located in close proximity to the line of carton travel, the chute being divided at its lower end into a pair of channels 152 and 153, and having an oscillating shutter, switch or guide member 154 pivotally mounted on a shaft 155. The shaft 155 has fixed thereto a lever 156 which, through link 157 and lever 158, is operated by a cam 159 bearing against the follower 160. The follower is carried by the lever 158 which is pivotally mounted as at 161, and the cam 159 is driven in timed relation with the machine by gearing generally indicated at 162. A spring 163 urges the mechanism to the position shown. The lever 156 has a pivoted connection 163 to a link 164 pivotally mounted at its upper end to a member 165 which is pivoted at 166, and has a portion 167 extending completely across the mouth of the chute 150.

From the arrangement thus described, the cam 159 will cause oscillation of the members 154 and 167 back and forth from their positions as seen in Figure 13 to those of Figure 14 in timed relation with other functions of the machine.

With the parts in the position of Figure 13 the finally closed cartons, one of which is indicated at M, will be ejected as follows: As the cage carrying the carton M passes by the segregator 150, the cam plate 145 engages the roller 144 and moves the upper assembly of retainer arms 112 to the neutral position as described, and as shown in Figure 6. Just as this movement is completed the cam plate 146 engages the roller 144 of the lower assembly of retainer arms 113 and rapidly moves them to the ejecting position shown in Figure 7. This action kicks the container outward from the bottom as indicated by the broken lines M1, the upper end of the carton being restrained from tipping by the member 167. The carton will then fall downward by gravity, and with the shutter 154 in the position shown, will be directed into the chute or channel 153 beneath which chute may be arranged a conveyor or other means indicated at 170 upon which the package will be received for disposition as desired. It will be received with the same end up as it had when in the cage.

Referring now to Figure 14, where the mem-

bers 154 and 167 have been moved to their alternate positions, the initially closed but empty cartons, one of which is indicated at N, will be ejected as follows: as the cage carrying the carton passes the segregator 150 the cam plate 143 will engage the roller 127 and move the lower assembly of retainer arms 113 to the neutral position of Figure 6. Just as this movement is completed the cam plate 142 engages the roller 127 of the upper assembly of retainer arms 112 and rapidly moves them to the ejecting position shown in Figure 7. This action kicks the empty container outward from the upper end as indicated by the broken lines N1, the carton pivoting at its lower end about a bar 171 which may be fixedly mounted across the mouth of the segregator, and suitably located to obstruct the movement of the lower end of the empty cartons, which empty cartons will have unfolded and downwardly extending end flaps which contact the bar. Thus the empty cartons will pivot about the bar 171 as they are ejected from the cages and will be turned end for end as at N2, whereafter they will fall by gravity through the chute 152 and onto a conveyor belt 172 to be carried to a filling machine if desired.

Figure 11 shows the profile of the cams 143 and 145, each of which have an inclined surface or rise 173 to engage the cam rollers as at 174 and move them to the position indicated at 175 which movement of the roller causes the retaining arms to be moved to the neutral position shown in Figure 6.

Figure 12 shows the profile of the cams 142 and 146, each of which have a gradual rise 176 to engage the rollers as at 177 and move them to the position indicated at 178, at which position of the rollers the retaining arms will be in the neutral position shown in Figure 6. Thereafter the rise 179 rapidly moves the rollers to the position indicated at 180, thus throwing the arms to the ejecting position of Figure 7.

It will be apparent how the platform member 114 acts as a gauge for the packages having one end closed, the closed lower end resting upon the platform. In Figure 10 we have shown how the platform also serves as a gauge for the initially squared up but unclosed cartons. As shown, the rear wall of the carton body 30 rests upon the member 114, and the extending portion of the liner 31a being of relatively flexible material, will be deformed as shown thus permitting retention of the carton in predetermined relation to the top sealing and folding devices of the machine.

In regard to the cages just described, it is to be pointed out that the trigger action thereof is important, that is, the fact that the insertion or introduction of a package automatically closes the cage. This movement being actuated by the introduction of the package itself.

It is also to be pointed out that the cage is adapted to either the open carton or the package having one end closed. In either case the gauge effect is provided so that either end of the carton can be sealed.

It is further to be pointed out that the fingers of the cage, not only by their shape but by their inherent mechanical spread in open position, make it particularly easy to insert a package.

It is finally to be pointed out in regard to these cages that they are adapted not only to the particular functions described in this application, but have many other uses and applications and can be used in conjunction with spreading devices for the liner or not, as desired.

In Figures 8 and 9, we have illustrated a machine comprising the improved cages with integrally associated spreading devices. As in the machine of Figures 1 and 2, a conveyor chain 4 operates about sprockets 2 and 3 to carry a series of blocks 7b about the machine. Each of the blocks has pivotally mounted thereon a turret assembly consisting of a gear 10b and a square plate 11b, the standards 110 and 111 of the cages being fixed to the plates 11b. At P is shown a container which is ready for final closure, its lower end having been previously sealed and folded rests upon the platform or gauge member 114 to bring the extending upper end of the liner 31 into proper alignment with the sealing and folding devices. At the position shown the fingers 107 and 108 of the spreading device descend into the liner mouth, the movement of the fingers being controlled by the cam element 200 engaging the roller 106. At Q the extending liner 31 has been elongated and flattened by the spreading action of fingers 107 and 108. As the carton is conveyed to the left the cam element 201 will cause the fingers to be withdrawn from the liner, but the liner will be retained in its flattened condition by the guide bars 203 and 204. It may be noted that the carton at Q is in the stage of initial closure, the lower unclosed end of the carton resting on the gauge 114, as described in conjunction with Figure 10.

As the carton travels to the position R the bar 205 may engage the upper margin of the liner 31 and fold it downward. With further travel of the carton the folded portion of the liner may pass between electrical heating elements indicated at 206, whereafter and as the carton approaches the position S, the pressure rollers 207 and 208 will engage the liner to affect sealing of the heated portion, the rollers 207 and 208 being driven in timed relation with the carton travel and having a resilient mounting, whereby dependable pressure between the rolls is assured. Thereafter the sealed and upstanding mouth of the liner will be engaged by a curved plate 209 arranged to fold or turn the mouth downwardly. At T the carton passes about the left side of sprocket 3 with its folded liner and end flaps being retained in their folded relations, as just described, by a bar 210 which bears lightly against the members.

As the carton arrives at the position U of Figure 9, the turret gear 10b will be engaged by rack 211 to rotate the carton retaining assembly through a quarter revolution and thereafter a pair of curved bars 212 and 213 engage and turn inwardly the end closure flaps 32 and 33 and the overlying portions of the liner mouth. This operation is completed as the carton arrives at position V, whereafter an overhead plate 214, which is cut away as at 215 and is continued at 216, bears against the folded members to retain them in position while the rack 217 causes the carton to again be rotated through a quarter revolution. The plate 214 is cut away as at 216 to provide clearance for the path of travel of the brackets 102 as the carton carrying assemblies are revolved. The brackets 102 are those which support the spreading devices of Figure 4.

As the carton approaches the position W, an arrangement of folding bars generally indicated at 218, engage the end closure flap 34 and fold same to its final folded position, whereafter and in the further course of travel, a rack 219 again rotates the carrier assembly through a quarter revolution. Thus at position X the end closure

is completed, but we prefer to pass the carton beneath a final pressure means as indicated by the roller 220, to insure complete closure of the end members. After passing beneath the pressure roller 220, the carrier assembly will be again rotated through a quarter revolution by virtue of the rack 221. This final rotation of the carrier assembly will return it to its original relation relative to direction of travel, as will be required for ejection of the carton and for reloading of the 10 carrier.

The ejection device is generally indicated at 222 and operates as was previously described in conjunction with Figures 13 and 14. While passing about sprocket 2, the arms of the cages may be returned to their neutral position by a cam track indicated at 223.

It is to be pointed out that the arrangement of the overhead bars for folding and closing the carton may be identical with that described in detail in our Patent 2,277,289 and for that reason have not been described in full detail herein.

From the foregoing it will be apparent that the combination of improved devices described makes possible a machine which requires no special spacing or speed limitation of the carrier members because they are not timed to any other moving device. The advantages obtained include the self-timing features of the machine, the elimination of moving parts, and the increased speed and efficiency that is thereby accomplished.

It will be understood that the principles disclosed herein are adapted to the sealing of projecting mouths of separate bags, as well as to the liners or liner mouth held within the carton. It will also be understood that the principles disclosed herein are adapted to folding and sealing carton flaps of unlined cartons as well, and it will be obvious that the cages described are an effective means of retaining packages, whether or not they have liners.

Modifications may be made in our invention without departing from the spirit of it. Having thus described our invention, what we claim as new and desire to secure by Letters Patent is:

1. In a packaging machine, a device for retaining erected carton bodies, including a support, means movable on said support for engaging carton bodies on their sides, certain of said means being movable to release said carton bodies, means on said machine to actuate said movable engaging means, and means operatively connected with said engaging means and located in the path of a carton body presented to said retaining means and hence actuated by the presentation of a carton body to said movable engaging means to move said means to carton gripping position.

2. In a packaging machine, a device for retaining erected carton bodies, including a support, opposed means pivoted on said support, and movable thereon to a position for gripping carton bodies, and to a position for releasing carton bodies, means operatively connected with said last mentioned means and actuated by the presentation of a carton body for moving said last mentioned means to carton gripping position, and means on said machine for moving said opposed means to carton releasing position.

3. In a packaging machine, a conveyor, a plurality of means on said conveyor for retaining erected carton bodies, said retaining means comprising oppositely mounted, movable, gripping arms coacting in one position to grip and re-

tain a carton body, said arms having extensions acting in another position of said arms to eject a carton body, said extensions forming means actuated by the presentation of a carton body to move said opposed arms to carton gripping position, and means on said machine engaging means operatively connected with said extensions to move said extensions to carton ejecting position.

4. In a device for retaining erected carton bodies, a support, opposed, pivotally mounted means on said support, each of said means including an arm adapted to lie behind a carton body, an angularly related arm adapted to engage a wall of said carton body and a finger adapted to engage over the front of a carton body, means interconnecting said pivoted members to enforce substantially equal and opposite movement thereof, and means in connection with said interconnecting means to establish three positions of said pivoted means, an ejection position in which said first mentioned arms cause a carton body to move substantially beyond said fingers, a reception position in which said arms and fingers are so placed as to permit the presentation of a carton body to said first mentioned arms, and a third position in which a carton body is gripped by said arms and fingers.

5. In a device for retaining erected carton bodies, a support, opposed, pivotally mounted means on said support, each of said means including an arm adapted to lie behind a carton body, an angularly related arm adapted to engage a wall of said carton body and a finger adapted to engage over the front of a carton body, means interconnecting said pivoted members to enforce substantially equal and opposite movement thereof, and means in connection with said interconnecting means to establish three positions of said pivoted means, an ejection position in which said first mentioned arms cause a carton body to move substantially beyond said fingers, a reception position in which said arms and fingers are so placed as to permit the presentation of a carton body to said first mentioned arms, and a third position in which a carton body is gripped by said arms and fingers, and means whereby said pivoted members may be moved to said several positions.

6. In a means for retaining carton bodies, supporting means, platform means on said supporting means to engage an end of a carton body to determine the longitudinal position of said carton body in said retaining means, movable fingers coacting to engage said carton body on three additional walls, means for actuating said movable fingers to gripping and non-gripping position, and means for ejecting a carton body from said retaining means when said fingers are in non-gripping position, said last mentioned means comprising extensions on said fingers lying behind said carton and engaging and moving said carton body when said fingers are moved to non-gripping position.

7. The structure claimed in claim 6 wherein there are duplicate sets of said fingers and wherein separate means are provided for actuating each set of fingers whereby during ejection one end of said carton body may be selectively moved farther than the other end thereof to control the position of said carton body as so ejected.

8. In a machine of the character described, a conveyor, spaced means on said conveyor for mounting carton body retaining means, and carton body retaining means on said spaced means,

11

each comprising a support, oppositely mounted pivoted means on said support for engaging carton bodies on their sides, said oppositely mounted pivoted means being arranged in spaced pairs and including ejection means, and means on said machine for selectively and sequentially actuating said spaced pairs.

9. In a device for retaining carton bodies, a base, spaced supports on said base, a platform connected to said supports for gauging the height of a carton body, spaced upper and lower arms pivoted to each of said supports and lying opposite each other, links connecting the said upper arms, a lever pivoted to one of said supports and connected to said links, a rod connected to said lever and links and having an end passing through a pivotal retainer on one of said supports, there being a spring on said rod, and latch means in connection with said rod for establishing several positions of said arms, the lower arms being provided with a similar link, lever, rod and latch arrangement, the interconnection between the links, lever and rod of each set of arms being provided with a separate cam follower, and said several arms bearing fingers adapted for engagement in one position of said arms with sides of a carton body.

10. In a device for retaining carton bodies, a base, spaced supports on said base, a platform connected to said supports for gauging the height of a carton body, spaced upper and lower arms pivoted to each of said supports and lying opposite each other, links connecting the said upper arms, a lever pivoted to one of said supports and connected to said links, a rod connected to said lever and links and having an end passing through a pivotal retainer on one of said supports, there being a spring on said rod, and latch means in connection with said rod for establishing several positions of said arms, the lower arms being provided with a similar link, lever, rod and latch arrangement, the interconnection between the links, lever and rod of each set of arms being provided with a separate cam follower, and said several arms bearing fingers adapted for engagement in one position of said arms with sides of a carton body, and the lever for the lower set of arms bearing a second cam follower.

11. In a device for retaining carton bodies, a base, spaced supports on said base, a platform connected to said supports for gauging the height of a carton body, spaced upper and lower arms pivoted-to each of said supports and lying opposite each other, links connecting the said upper arms, a lever pivoted to one of said supports and connected to said links, a rod connected to said lever and links and having an end passing through a pivotal retainer on one of said supports, there being a spring on said rod, and latch means in connection with said rod for establishing several positions of said arms, the lower arms being provided with a similar link, lever, rod and latch arrangement, the interconnection between the links, lever and rod of each set of arms being provided with a separate cam follower, said several arms bearing fingers adapted for engagement in one position of said arms with sides of a carton body, and the lever for the lower set of arms bearing a second cam follower, one set of said arms at least being so shaped as in one position to eject a carton body from said platform.

body from said platform.

12. In a device for retaining carton bodies, a base, spaced supports on said base, a platform connected to said supports for gauging the height of a carton body, spaced upper and lower arms

12

pivoted to each of said supports and lying opposite each other, links connecting the said upper arms, a lever pivoted to one of said supports and connected to said links, a rod connected to said lever and links and having an end passing through a pivotal retainer on one of said supports, there being a spring on said rod, and latch means in connection with said rod for establishing several positions of said arms, the lower arms being provided with a similar link, lever, rod and latch arrangement, the interconnection between the links, lever and rod of each set of arms being provided with a separate cam follower, and said several arms bearing fingers adapted for engagement in one position of said arms with sides of a carton body, and the lever for the lower set of arms bearing a second cam follower, one set of said arms at least being so shaped as in one position to eject a carton body from said platform, there being on one of said supports at least stop means coacting with said levers to fix an inward position of said arms.

13. In a packaging machine means for conveying a series of package holding devices, and package holding devices each of which includes movable means to grip and release a package, and means operatively connected with said movable means for moving them to gripping from releasing positions, said last mentioned means lying in the path of presentation of a package to a package holding device so as to be actuated by contact with the package as presented to the package holding device.

14. In a packaging machine, means for conveying a series of devices for holding erected cartons upon which operations are to be performed, each such device having opposed angular pivoted arms for engaging an erected carton body in one position, said arms being movable on their pivots to a carton releasing position, dead center mechanism for holding said arms in said two positions, and opposed extinctions on said arms and movable therewith into the space between said arms when said arms are moved to releasing position, so that 40 when a carton body is presented to said device, brought against said extensions and moved to a position between said arms, said extensions will move said arms past dead center to carton engaging position.

SAMUEL BERGSTEIN.
LOUIS J. VAN GUELLEN.
